The ornamental design for a business card holder for vertically-oriented cards, as shown and described.

DESCRIPTION

FIG. 1 is a front elevational view of a business card holder for vertically-oriented cards showing my new design;

FIG. 2 is a rear elevational view thereof, the opposite end having the same appearance;

FIG. 3 is a top plan view thereof;

FIG. 4 is a bottom plan view thereof;

FIG. 5 is a right side elevation view thereof, the left elevational view being a mirror image; and,

FIG. 6 is a perspective view thereof.
